United States Patent Office

Des. 208,974
Patented Oct. 24, 1967

208,974

MEDALLION

Leland George Stone, Mundelein, Ill., assignor to Amerock Corporation, Rockford, Ill., a corporation of Connecticut

Filed Jan. 9, 1967, Ser. No. 5,349

Term of patent 14 years

(Cl. D13—1)

FIG. 2 is a side view as seen from the right of FIG. 1.

FIG. 3 is a sectional view taken along the line 3—3 in FIG. 1.

FIG. 4 is a sectional view taken along the line 4—4 in FIG. 1.

I claim:

The ornamental design for a medallion, as shown.
